DESIGN FOR AN ATOMIZER

Paul B. Brown, Toledo, Ohio

Application May 22, 1933. Serial No. 48,180

Term of patent 7 years

To all whom it may concern:

Be it known that I, PAUL B. BROWN, a citizen of the United States, and resident of Toledo, county of Lucas, State of Ohio, have invented a new, original, and ornamental Design for an Atomizer, of which the following is a specification, reference being had to the accompanying drawing, forming a part thereof.

In the drawing the single figure is a side elevation of an atomizer showing my new design, the bottle and the bulb being shown in dotted lines.

The essential feature of the design resides in the shape of the bottle top and of the bulb attaching means in combination therewith, as shown in full lines in the drawing.

I claim:

The ornamental design for an atomizer, substantially as shown and described.

In testimony whereof I have hereunto signed my name to this specification.

PAUL B. BROWN.
